UNITED STATES PATENT OFFICE

2,666,331

ENGINE TURNING GEAR

Robert Philip Hewson, Egham, England, assignor
to The Stanley Engineering Company Limited,
Egham, England

Application December 11, 1952, Serial No. 325,260

Claims priority, application Great Britain
January 9, 1952

6 Claims. (Cl. 74—7)

1

This invention relates to engine turning gear and has for its main object to provide an improved form of turning gear for effecting the starting of an internal combustion engine.

The invention is mainly suitable for use with light engines, and is thus particularly applicable to internal combustion engines for use in invalid carriages, motor cycles, motor cars and other light vehicles.

The invention consists in a turning mechanism for starting internal combustion engines, comprising a belt drive for coupling the engine shaft with a starter device, said belt drive passing round a driving pulley adapted to move longitudinally in response to rotation by said starter device, and a driven pulley associated with said engine shaft, said driven pulley being formed in two parts, one of which is freely mounted and the other of which is keyed to the engine shaft whereby the belt drive is adapted to move from one part of said pulley to the other part in response to the longitudinal movement of said driving pulley and thereby effect the turning of the engine shaft.

According to the preferred arrangement, the part of the driven pulley which is keyed to the engine shaft forms part of the engine flywheel, and the freely mounted part of the pulley is mounted in bearings carried on the engine shaft.

The invention will be more completely understood from the following detailed description which is given in conjunction with the accompanying drawings, in which:

Figures 1 and 2 are front and fragmentary side views respectively of an internal combustion engine which is suitable for use in an invalid carriage, motor cycle, car or other light vehicle, and in which the invention is embodied.

Referring now to these drawings, the engine shown is constructed in substantially orthodox form, comprising a main supporting frame 1 on which is mounted a cylinder 2, a carburetor 3, a crank case 4, and an electric starter device 5 of any well known form, this starter device being secured in position in such a way that the driven shaft 6 of the starter device is disposed substantially parallel to the engine shaft 7. The driven shaft 6 of the starter device 5 extends some distance beyond the starter device casing and part of this shaft is provided with a helical thread 8 on which is mounted a V-shaped pulley 9 preferably formed of cast iron, this pulley having an internal helical thread 10 engaging with the helical thread 8 on the shaft so that this pulley 9 is adapted to rotate with the shaft 6 when the latter is driven by the starter 5 but is also

2

adapted to slide along the shaft in response to relative rotation between the shaft and the pulley as determined by the helical thread. This pulley 9 constitutes the driving pulley of the turning gear and is adapted to be coupled to the engine shaft 7 by a driving belt 11 which passes round this pulley 9 and also round a second or driven pulley mounted on the engine shaft. This latter pulley, however, is formed in two parts 12 and 13, and each part is of sufficient width to carry the driving belt 11 which is thus free to slide from one part of the pulley to the other. One part 13 of this pulley is formed as an extension of the flywheel 14 so that it is permanently keyed to the engine shaft so as to rotate with it, but the other part 12 is freely mounted for independent rotation and is conveniently mounted in bearings 14 disposed in a ball race 15 secured by bolt 16 to an internal shaft 17 screwed into the interior of the engine shaft 7 on which the flywheel 14 is mounted.

The driving and driven pulleys are so relatively positioned that when the engine is stationary the freely mounted part 12 of the driven pulley is disposed immediately opposite or below the driving pulley 9 so that the belt is perfectly free to rotate. When, however, current is applied to the starting device 5, e. g. by the pressing of a button or the closure of a switch, the sudden rotation of the shaft 6 of the starter device acting against the inertia of the aforesaid driving pulley 9 causes the latter to slide inwards along the helical thread 8, thus causing the driving belt 11 to slide on to the part 13 of the driven pulley formed on the engine flywheel and thus rotate the latter. As soon as the engine starts up, however, and current is disconnected from the starter device 5, the driving pulley 6 will slide back into its original position and cause the driving belt 11 to slide back on to the freely mounted part 12 of the driven pulley, thereby allowing the engine flywheel and shaft to run freely and leaving the starter gear in readiness for the next operation with the belt 11 and associated pulleys stationary.

It will thus be seen that by means of this arrangement a very smooth form of starter mechanism is provided, and the customary banging which normally takes place by a pinion wheel being flung into engagement with the flywheel teeth of the engine is entirely obviated. Moreover, in view of the fact that the driving belt and its associated pulleys remains stationary except when it is in actual operative movement, all un-

necessary wear on the driving belt is substantially eliminated.

I claim:

1. Engine turning mechanism for starting internal combustion engines, comprising a belt drive for coupling the engine shaft with a starter device, said belt drive passing round a driving pulley adapted to move longitudinally in response to rotation by said starter device, and a driven pulley associated with said engine shaft, said driven pulley being formed in two parts, one of which is freely mounted, and the other of which is keyed to the engine shaft, whereby the belt drive is adapted to move from one part of said pulley to the other part in response to the longitudinal movement of said driving pulley and thereby effect the turning of the engine shaft.

2. Engine turning mechanism for starting internal combustion engines, comprising a belt drive for coupling the engine shaft with a starter device, said belt drive passing round a driving pulley adapted to move longitudinally in response to rotation by said starter device, and one or other of two pulleys disposed adjacent one another, one of such driven pulleys being freely mounted, and the other being formed on the engine flywheel, the belt drive being free to move from one driven pulley to the other in response to the longitudinal movement of said driving pulley so as to effect the turning of the engine flywheel and shaft.

3. Engine turning mechanism according to

claim 1, wherein the part of said driven pulley which is keyed to the engine shaft forms part of the engine flywheel.

4. Engine turning mechanism according to claim 1, wherein the freely mounted part of said driven pulley is mounted in bearings carried on the engine shaft.

5. Engine turning mechanism according to claim 1, wherein said driving pulley is provided with an internal helical thread engaging with a corresponding helical thread on the shaft of said starter device, whereby relative rotation between the shaft and the pulley effected by said starter device, brings about a longitudinal movement of the pulley with respect to the shaft.

6. Engine turning mechanism according to claim 1, wherein said driving pulley is so arranged as to be disposed substantially opposite the freely mounted part of said driven pulley when the engine is stationary, whereby the longitudinal movement of said driving pulley brought about by said starter device causes said belt drive to move over from the freely mounted part of said driven pulley on to the part keyed to the engine shaft.

ROBERT PHILIP HEWSON.
